(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image in the sequence showing our new design; FIG. 2 is a second image thereof;

FIG. 3 is a third image thereof;

FIG. 4 is a fourth image thereof;

FIG. 5 is a fifth image thereof; and,

FIG. 6 is a sixth image thereof.

In the drawings, the outermost dash-dash broken lines are for the purpose of illustrating the display screen or portion thereof, and form no part of the claimed design. The other dash-dash broken lines are for the purpose of illustrating portions of the animated graphical user interface that form no part of the claimed design.

The dot-dash-dot broken lines are for the purpose of illustrating the boundaries of the claim, and form no part of the claimed design.
